UNITED STATES PATENT OFFICE.

WILLIAM STEPHEN BOYCE, OF PITTSBURGH, PENNSYLVANIA, ASSIGNOR TO THE RAIL JOINT COMPANY, A CORPORATION OF NEW YORK.

RAIL-JOINT.

1,223,251.

Specification of Letters Patent. Patented Apr. 17, 1917.

Application filed August 15, 1916. Serial No. 115,056.

To all whom it may concern:

Be it known that I, WILLIAM S. BOYCE, a citizen of the United States, residing at Pittsburgh, in the county of Allegheny and State of Pennsylvania, have invented certain new and useful Improvements in Rail-Joints, of which the following is a specification.

This invention relates to rail joints, more particularly of the continuous type, and has special reference to a novel improvement therein, whereby the full clamping effect of all the rail bearing faces of the joint bar are utilized to a maximum extent.

15 A primary object of the invention is to provide an improvement in the continuous type of joint bar, which will to a large degree, counteract a faulty application of the bar through carelessness of the track-men.

20 It is only through such faulty application that the continuous type of bar will not have a proper fit to the rail and not maintain its maximum supporting effect, and it is, therefore, the purpose of the present invention to obviate the undesirable conditions arising from the neglect of the track-men to drive the bars in at the base so that the bearing faces of the bar will not coincide with the fishing space and the base of the

25 rail. This neglect on the part of the track-men usually results in cocked or canted bars as well as the reduction of the bearing of the bar on the rail, thus leaving opportunity for the development of play between the head of the rail and the bar, which allows the "knitting" of the rail ends, and in some instances may possibly cause rail flange breakage. Furthermore, it has been found that owing to the slight variation in

30 the size of rails, the joint bars often fit perfectly in the fishing space thereof while the base fit is loose, thus impairing the supporting effect of the base of the bar.

Accordingly, the present invention contemplates a joint bar of such a character that regardless of carelessness in application, it will properly contact throughout its length with the underside of the rail head, the upper side of the base flange, and the bottom of the rail base. In this connection, it may also be noted that a novel and distinctive feature of the invention resides in providing a joint bar having bearing faces, which may be made at all times to effectu-

ally maintain a maximum clamping efficiency.

With the above and other objects in view which will more readily appear as the nature of the invention is better understood, the same consists in the novel construction, combination and arrangement of parts hereinafter more fully described, illustrated and claimed.

A preferred and practical embodiment of the invention is illustrated in the accompanying drawings, in which—

Figure 1 is an end view of the improved rail joint (with the rail in section) showing the initial relation of the joint bars to the rails, the bearing faces of the bar being somewhat exaggerated to more clearly show the invention.

Fig. 2 is a bi-sected cross-sectional view showing the position of one of the joint bars after the same has become slightly worn and the bolts have been tightened to take up the wear.

Similar reference characters designate corresponding parts throughout the several figures of the drawings.

In carrying forward the invention the improvements herein specified and claimed are particularly applicable to the continuous type of rail joint bar, that is, a rail joint bar which includes a rail supporting base member engaging beneath the rail base, as well as an upright member fitting the fishing space of the rail and having a bearing contact with the underside of the rail head and with the upper side of the rail flange. The exact section or shape of this bar is not material to the present invention, nor the particular distribution of metal therein, but the essential characteristics thereof are necessarily embodied in a bar of the continuous type, that is to say, a bar which comprises, generally, an upright member 1 having an upper head portion 2 for engaging beneath the rail head and against the rail web, a foot flange 3 which overlies and contacts with the rail flanges, and an integral inwardly extending base member 4, which underlies and engages the base of the rails.

Referring to the novel formation of the rail bearing faces of the present joint bar, it will be observed from the drawings that the head portion 2 thereof is provided with a top supporting surface 5, which includes

the primary and secondary rail bearing faces 6 and 7, arranged at different angles, the former having the same angle or inclination as that of the underside of the rail head, while the latter face is disposed at a lesser angle than the said primary face to the perpendicular axis of the bar. In other words the primary bearing face 6 of the joint bar is arranged at the same angle to the vertical axis of the joint bar as the inclined underside of the rail head is to the vertical axis of the rail, while the secondary face is arranged at a lesser angle to the vertical axis of the bar and adjoins the said primary bearing face. The head portion of the bar 2 further includes an inwardly projecting fulcrum rib 8, the surface of which is rounded or curved to provide a fulcruming abutment adapted to contact as at 10 with the rail web when the joint bar is applied to the rail. Thus, it will be apparent that the head portion 2 of the bar is so formed as initially to have a limited area of contact throughout the length of the primary rail bearing face 6 with the underside of the rail head adjacent the outer side of the latter, and the projection 8 bearing against the web of the rail in such a way as to constitute a fulcrum point. The underside of the foot flange 3 is also provided with a rail contacting surface 11 which includes the inclined primary bearing face 12 arranged at the same inclination or angle as that of the upper inclined face of the rail flange, and also the secondary bearing face 13 adjoining the primary bearing face, which secondary face is arranged at a lesser angle than the latter to the perpendicular axis of the bar. This rail contacting surface 11, through the face 12, provides a limited area of contact for the foot of the bar with the base flange of the rails, while the secondary bearing face opens into the groove in which the outer edge of the base flange of the rail has a relatively loose fit.

The supporting base 4 of the bar, which underlies the base flange of the rails, is preferably provided adjacent the edge thereof with a substantially horizontal rail bearing portion 14 constituting a primary bearing face, while at a point 15 the latter joins a secondary bearing face 16, disposed at an angle to the primary bearing face, which, as shown, in the present instance is preferably horizontal.

From the foregoing, it will be apparent that the joint bar of the present invention is formed with a primary bearing face disposed at the same angle or inclination as the complemental bearing face of the rail, and with an initially non-contacting secondary bearing face. This secondary bearing face on the head of the bar diverges inwardly with relation to the underside of the

rail head, and the secondary faces on the foot and base sections of the bar bear an outwardly divergent relation respectively to the outer side of the base flange of the rail, and to the bottom of the rails. Accordingly, when the joint bars are applied to the rails, as shown in the drawings, the same will initially contact with the rails along the primary rail bearing faces 6, 12 and 14, and also at the fulcrum point 10, while the secondary rail bearing faces 7, 13, and 16 provide a wear-take-up clearance at the underside of the rail head, upper side of the base flange and at the underside or bottom of the rail bases. These clearances are respectively designated as *a*, *b*, and *c*, and only exist in the initial application of the joint bars to provide sufficient room for adjustment and enable the secondary rail contacting faces 13 and 16 to flushly contact throughout their length with the complemental portions of the rails upon the tightening of the joint bolts after the joint bars wear, through the assistance of the fulcrum bead or rib 8.

Since the head of the bar engages both the head and the web of the rail continuously, and fulcrums against the rail web, the joint bolts will, under all conditions, exert a persisting turning force on the web of the bar to maintain the rail-supporting base thereof in rigid contact with the rail. As the bearing faces of the bar wear this persisting clamping force of the joint bolts rocks the bar inwardly at the base thus bringing all of the secondary bearing faces into supporting engagement with the rail, and thereby maintain the proper supporting effect of the bar. That is to say, the clearance spaces *a*, *b*, and *c* disappear and the primary bearing faces also wear and merge into the secondary bearing faces.

Furthermore, the space of the groove G in the bar provides ample clearance for the adjustment of the bar in relation to the rail, and with the increased rail flange clearance, the bars may be folded tightly to provide a yielding or springy base to readily fit varying thicknesses of base flanges. That is to say, in providing the enlarged groove G, the base of the bar may be folded more tightly than usual, whereby, in the case of a thin based rail, the base of the bar would be drawn in slightly more than in the case of a perfectly rolled rail, while on the thick based rail, the spring or yield in the base of the bars would be sufficient to allow the bar to be drawn "home," and at the same time afford a support at the base of the rails.

A bar having the novel features described is automatically pulled in at the base by the tightening of the joint bolts and always maintains an efficient rail support.

Without further description, it is thought that the many features and advantages of

the present invention will be readily apparent, and it will, of course, be understood that minor changes in the form, appearance and details of construction may be resorted to without departing from the spirit of the invention or scope of the appended claims.

I claim:

1. A rail joint including the rail, and a joint bar having a primary and a secondary rail bearing face on each of its rail engaging surfaces.

2. A rail joint including the rail, and a joint bar having a head, foot and base member each of which is provided with a primary and secondary rail engaging face.

3. A rail joint including the rail, and a joint bar having a head, foot, and base member each having a primary bearing face engaging the rail in the initial application of the bar and a secondary rail bearing face initially out of contact with the rail.

4. A rail joint including the rail and a joint bar having a primary and a secondary rail bearing face on each of its rail engaging surfaces, said primary bearing faces being disposed in the same plane as the faces of the rail with which they contact, and said secondary rail bearing faces being disposed at an angle thereto.

5. A rail joint including the rail and a joint bar having a plurality of rail engaging faces, said rail engaging faces having a limited contact with the rails in the initial application thereof.

6. A rail joint including in combination with the rails and joint bolts, a joint bar having a plurality of rail engaging surfaces, and a fulcrum element formed with the bar and contacting with the rail web, each rail engaging face having a limited area of contact with the rail in the initial application of the bar, and a larger area of contact with the rail when the initial points of contact wear down and the bar is rocked on the fulcrum element by the tightening of the bolts.

7. A rail joint including the rail and a joint bar having a base member and provided with a primary and a secondary rail bearing face at the head of the bar, the

underside of the foot flange, and at the upper side of the base member, said primary faces at the head and foot of the bar being disposed at the same angle as the corresponding contacting faces of the rails, and all of said secondary rail bearing faces being disposed at a lesser angle to the perpendicular axis of the bar than said primary faces.

8. A rail joint including the rail and a joint bar including a top supporting surface having a primary and a secondary rail bearing face, a foot flange having primary and secondary rail bearing faces at its underside, a base member also having a primary and a secondary rail bearing face, and a fulcrum element located between the said rail bearing faces at the top of the bar head and underside of the foot flange.

9. A rail joint including the rail and a joint bar having a base member and provided with a primary and a secondary rail bearing face at the head of the bar, underside of the foot flange and upper side of the base member, and a fulcrum rib formed on the head portion of the bar and adapted to contact with the rail web between the head and foot flange of the bar.

10. A rail joint including the rail and a joint bar having a base member provided with primary and secondary rail bearing faces, a top supporting surface having a primary bearing face disposed at the same angle as the inclined underside of the rail head, and a secondary rail bearing face adjoining said primary face and disposed at a lesser angle to the perpendicular axis of the bar than said primary face, and said head also having a fulcrum rib adjoining said secondary rail bearing face and adapted to contact with the web of the rail, and primary and secondary rail bearing faces also located at the underside of the foot flange.

In testimony whereof I hereunto affix my signature in the presence of two witnesses.
